LIGHTNING ARRESTER

Eugene J. De Val, Pitcairn, Pa., assignor to Westinghouse Electric Corporation, East Pittsburgh, Pa., a corporation of Pennsylvania

Application August 24, 1951, Serial No. 243,496

8 Claims. (Cl. 313—321)

1

The present invention relates to lightning arresters, and more particularly to a compact and simplified construction for lightning arresters of the expulsion type.

Expulsion type lightning arresters consist essentially of spaced electrodes disposed in a vented arcing chamber which is lined with, or contains, insulating material capable of evolving substantially un-ionized gas when exposed to an electric arc. When a discharge occurs between the electrodes, a large quantity of gas is evolved which is expelled in a blast through the vent, blowing out the arc gases and deionizing the arc path to extinguish the arc, thus interrupting the power current which tends to flow through the arrester to ground following the discharge of a lightning surge. In the usual construction of arresters of this type, the arcing chamber consists of a tubular structure of hard fiber, or other suitable gas-evolving material, with electrodes disposed at the ends of the tube, at least one of the electrodes extending into the tube, and at least one of the electrodes being vented. A plug or filler of gas-evolving material is usually placed in the tube between the electrodes to restrict the area of the arc path, and to increase the amount of gas-evolving material exposed to the arc, so as to improve the current-interrupting ability of the arrester.

A steel sleeve is usually placed over the outside of the tubular structure and connected to the ground electrode, to provide mechanical reinforcement against the high bursting pressures which occur in the tube when the arrester operates, and to function as an electrostatic shield to improve the spark-over characteristics of the arrester. The presence of this conducting shield on the outside of the tube, at ground potential, makes it necessary to provide adequate insulation between the shield and the line electrode to prevent any possibility of external flashover on the outside of the tube. In the prior practice, the necessary insulation has sometimes been provided by increasing the length of the tube above the shield sufficiently to provide a long enough surface between the upper end of the shield and the nearest exposed part of the line electrode to insure against external flashover. This method of obtaining adequate insulation is undesirable, however, because of the greatly increased length of the tube, which makes the arrester undesirably long, and which substantially increases the cost because of the much longer tube and the correspondingly long porcelain housing required. Another construction which has been

2

used to obtain adequate insulation employs a reservoir of liquid, or semi-liquid, insulating gum above the end of the shield with insulating barrier members containing the gum and sealing the structure. This construction, however, requires a number of extra parts to contain the gum and form the necessary seal, and involves considerable difficulty in assembly as well as requiring increased length, all of which increase the cost of the arrester.

10 The principal object of the present invention is to provide an expulsion type lightning arrester in which adequate insulation against external flashover is provided in a simple manner without increasing the length or cost of the arrester.

15 Another object of the invention is to provide an expulsion type lightning arrester of minimum length and low cost, but which has adequate insulation to prevent external flashover of the expulsion tube.

20 A further object of the invention is to provide an expulsion type lightning arrester having a minimum number of parts and a simplified construction which permits rapid and easy assembly, thus substantially reducing the cost.

25 A still further object of the invention is to provide an expulsion type lightning arrester having a low-cost terminal cap for covering and enclosing the arrester terminal and line lead, and which can readily be applied to or removed from the arrester and which is not subject to breakage.

30 Other objects and advantages of the invention will be apparent from the following detailed description, taken in connection with the accompanying drawing, in which:

35 Figure 1 is a vertical sectional view of a lightning arrester embodying the invention, and

40 Fig. 2 is a sectional view of a terminal cap taken on a plane substantially at right angles to the plane of Fig. 1.

45 The invention is shown in the drawing embodied in an expulsion type lightning arrester having a tube or tubular structure 1, which forms the arcing chamber of the arrester, and which is made of hard fiber, or other suitable insulating material which is capable of evolving substantially un-ionized gas when exposed to an electric arc, and which has sufficient mechanical strength. An upper electrode member 2 is disposed in the upper end of the tube 1. The electrode 2 is shown as a steel sleeve which fits tightly in the tube 1, and which is threaded in the upper end of the tube to hold the electrode securely in position against the strong axial

thrust which occurs when the arrester operates. A lower electrode member 3 is provided at the lower end of the tube 1. The lower electrode 3 is shown as a generally cylindrical steel member which fits against the lower end of the tube 1, and which is provided with a plurality of vent openings 4 to permit discharge of the gas generated in the arrester during operation.

A generally cylindrical plug or filler 5 of insulating, gas-evolving material, such as hard fiber, is preferably inserted in the bore of the tube 1 between the electrodes 2 and 3 to restrict the arc path. Any suitable type of filler may be used but it is preferred to utilize the type of filler disclosed and claimed in my copending application Serial No. 182,994, filed September 2, 1950, and assigned to the Westinghouse Electric Corporation. As more fully explained in that application, the filler 5 is generally cylindrical and has a helical groove 6 in its surface extending from end to end of the filler. When the arrester operates, the gas evolved from the tube and filler flows through the groove and forces the arc into a helical path, elongating the arc and increasing the arc voltage, to facilitate its interruption. While this helically grooved type of filler is preferred because of the improved current-interrupting ability and increased life obtained, it will be apparent that any other type of filler, either loose or fixed in position, might be used if desired.

A conducting shield and reinforcing member 7 is disposed on the outside of the tube 1. The shield 7 is preferably a steel sleeve which fits tightly over the tube 1, and which is held in position by annular indentations or crimps 8 which engage corresponding annular depressions on the tube 1 to prevent axial displacement between the tube and shield. The lower electrode 3 is provided with an annular recess 9 and the lower end of the shield is crimped or rolled into this recess to retain the electrode 3 in position and to effect electrical contact between the shield and the lower electrode. The shield 7 extends from the lower end of the tube 1 towards the upper end and, as shown in the drawing, it preferably extends far enough to overlap the upper electrode 2 a substantial distance, so that the shield 7 functions to lower the critical spark-over voltage of the arrester by concentrating the voltage stress adjacent the lower end of the electrode 2 immediately before breakdown.

It will be evident that since the shield 7 extends towards the upper end of the tube 1, it is necessary to provide means to prevent external flashover on the outside of the tube between the electrode 2 and the shield 7. This result has sometimes been accomplished heretofore by extending the tube 1 above the end of the shield 7 for a great enough distance to provide the necessary insulation, but this construction requires an extremely long tube, and is unsatisfactory because of the increased cost of such a tube and of the required housing, and because it results in an undesirably long arrester. Another construction which has been used involves the use of a liquid, or semi-liquid, insulating gum surrounding the upper end of the tube 1 above the shield, with insulating barrier members to contain the gum and to seal it in place, but this type of construction results in a complicated structure requiring numerous extra parts and considerable difficulty in assembly of the device, as well as undesirably increasing the length.

In accordance with the present invention, adequate insulation between the shield and the up-

per electrode is obtained in a simple and inexpensive manner. For this purpose, the upper end of the tube 1 above the shield 7 is externally tapered, as indicated at 10 and an insulating member or barrier 11 is provided which encloses the tube 1 and extends axially over the shield 7 toward the lower end of the tube, the barrier being made long enough to provide the necessary insulation. The insulating barrier 11 is shown as being generally cylindrical and is internally tapered at its upper end to engage the tapered portion 10 of the tube 1. The insulating barrier 11 may be made of any suitable plastic insulating material which has some flexibility or resiliency, polyethylene being a very suitable material for this purpose. The internally tapered upper end of the insulating barrier 11 is designed to have an appreciable interference fit with the tapered end 10 of the tube 1, that is, it is designed so that its internal dimensions are slightly smaller than the external dimensions of the tapered part of the tube 1.

In assembling the device, a thin layer of insulating gum is applied to the tapered surface 10 of the tube 1 and the insulating barrier 11 is then placed over the tube 1 and forced into place, the insulating gum serving to exclude any air between the engaging tapered surfaces so that a tight sealing engagement is obtained. A washer 12 is placed on top of the barrier 11 and a nut 13 is threaded on the upper end of the electrode 2 to clamp the insulating barrier 11 in place on the tube 1. The insulating barrier 11 thus surrounds and encloses the tube 1 and shield 7 and extends axially over the shield towards the lower end of the tube, providing a long insulating path between the upper electrode 2, and associated conducting parts, and the nearest exposed part of the shield 7. The lower part of the barrier 11 may be tapered in thickness, as shown, to facilitate manufacture and reduce the cost, since it is not necessary for this part of the barrier to have great mechanical strength.

It will be seen that adequate insulation is provided to prevent external flashover of the tube 1, but that the length of the structure is not increased over that required by the necessary length of the internal arc path. Thus, an arrester is provided which is of minimum length and of simple, low-cost construction, and which can readily be assembled without difficulty.

The arrester is contained in a generally cylindrical housing 14 of porcelain, or other suitable weather-resistant insulating material. The lower end of the housing is closed by a metal washer 15 which surrounds the lower electrode 3 and engages an external shoulder on the electrode, and which is clamped against an internal shoulder in the housing 14, a gasket 16 being interposed between the washer 15 and housing 14 to seal the interior of the housing. The washer 15 has an extending lug 17 on one side which is bent downward and carries a terminal device 18, of any suitable type, for connection of a ground lead to the lower electrode 3. The housing 14 preferably has a recess or opening 19 for the terminal device 18 so that it is accessible but is substantially enclosed within the housing.

A series spark gap is always utilized with expulsion type lightning arresters so that the fiber tube will not be continuously subjected to the normal line voltage. Any suitable type of series gap may be used with the arrester of the present invention, and the drawing shows a semi-enclosed gap of the type disclosed and claimed in my co-

pending application Serial No. 243,497, filed August 24, 1951. This gap device is contained in a porcelain housing which consists of two members 20 and 21 glazed, or otherwise joined together, to form a unitary housing. A threaded stud 22 extends through a central opening in the lower housing member 20 and an electrode member 23 is threaded on the upper end of the stud 22 within the gap housing. A nut 24 clamps the stud and electrode to the gap housing. The lower end of the stud 22 is threaded into a tapped hole in the top of the upper electrode 2 of the expulsion assembly, to secure the gap housing in place and to effect electrical connection between the electrode 23 and the electrode 2. A gasket 25 is preferably interposed between the top of the housing 14 and the bottom of the gap housing, and when the stud 22 is threaded into the electrode 2 and tightened, the gap housing is firmly secured on the housing 14 and the washer 15 is drawn tightly against the housing 14.

The upper electrode of the series gap consists of a threaded stud 26 extending through a central opening in the upper part 21 of the gap housing and positioned by means of a U-shaped retaining member 27 which engages a slot in one side of the stud 26 and is seated in a recess in the housing 21. The upper gap housing part 21 has openings 28 to permit visual inspection of the gap between the electrodes 23 and 26, the gap being sufficiently enclosed, however, to prevent accidental bridging or contact, as more fully explained in my above-mentioned copending application. A nut 29 is threaded on the upper end of the stud 26 to retain it in position, and suitable terminal means 30 are provided on the stud for clamping a line lead thereto, so that the stud 26 serves as a line terminal device for the arrester.

It is highly desirable that all live parts of the arrester be enclosed to prevent accidental contact. The electrodes of the series gap are enclosed in the gap housing, as described, and a cap member 31 is provided for enclosing the arrester terminal and line lead. Cap members have been used heretofore for enclosing the terminals of lightning arresters, and other electrical devices, but the caps which have been available have been unsatisfactory where the cap must be capable of being removed and replaced. Previous devices have usually required some type of metallic spring to hold the cap in position, and to permit it to be readily removed and returned, but such devices are not satisfactory because of the possibility of rapid corrosion of the metallic spring parts, and also because of the relatively hard, brittle material which previously had to be used for such caps, which made it relatively easy to break them in the course of handling. In accordance with the present invention, a cap member is provided for covering the terminal and line lead which avoids these disadvantages and which can readily be applied and removed without risk of breakage.

The cap 31 is made of a flexible, or somewhat resilient, plastic insulating material, the preferred material being polyethylene. The cap 31 is a generally cup-shaped member with slots or recesses 32 in opposite sides for entrance of the line lead. A central boss or enlargement 33 is formed on the inside surface of the top of the cap and has a central opening which is designed to have an interference fit on the terminal stud 26. The boss 33 is preferably split on opposite sides, as indicated at 34. It will be apparent that the cap 31 can readily be applied by forcing the central opening over the top of the terminal stud, so

that it is retained in position by the resilient engagement of the sides of the boss 33 with the stud, and that the cap can readily be removed by pulling it off without damaging the cap. There are no metallic parts to corrode, and polyethylene, which is the preferred material, has good weathering properties, so that its life is very long, and is sufficiently flexible to avoid any risk of breakage. Thus, a terminal cover has been provided which is simple and readily applied, and which can be produced at low cost, and avoids the disadvantages of the previous types of terminal covers which have been available.

It should now be apparent that a construction has been provided for lightning arresters of the expulsion type which provides a compact and low-cost arrester of simple construction but with fully adequate insulation to prevent any possibility of external flashover. The new arrester can readily be assembled and provides a desirable type of construction in that all live parts are fully enclosed, so that there is no risk of accidental contact or of accidentally bridging the series gap. The terminal cover which encloses the line terminal and lead is a simple, low-cost member which is not subject to breakage and which is easily applied and removed.

It will be apparent that although a particular embodiment of the invention has been shown and described for the purpose of illustration, various other embodiments and modifications are possible within the scope of the invention, and it is to be understood that the invention is not limited to the specific details of construction shown, but in its broadest aspects, it includes all equivalent embodiments and modifications which come within the scope of the appended claims.

I claim as my invention:

1. A lightning arrester comprising a tubular structure having an internal surface of material capable of evolving gas when exposed to an electric arc, electrode means disposed at opposite ends of said tubular structure, at least one of said electrode means extending into the tubular structure to establish an internal discharge path between the electrodes, and at least one end of the tubular structure being vented, a conducting shield extending over a substantial part of the outer surface of the tubular structure, and an enclosing insulating member directly engaging one end of the tubular structure adjacent the end of the shield and extending axially over said shield.

2. A lightning arrester comprising a tubular structure having an internal surface of material capable of evolving gas when exposed to an electric arc, electrode means disposed at opposite ends of said tubular structure, at least one of said electrode means extending into the tubular structure to establish an internal discharge path between the electrodes, and at least one end of the tubular structure being vented, a conducting shield disposed on the outside of the tubular structure and extending from one end thereof toward the other end, and an enclosing insulating member directly engaging said other end of the tubular structure adjacent the end of the shield and extending axially over said shield.

3. A lightning arrester comprising a tubular structure having an internal surface of material capable of evolving gas when exposed to an electric arc, electrode means disposed at opposite ends of said tubular structure, at least one of said electrode means extending into the tubular structure to establish an internal discharge path be-

tween the electrodes, and at least one end of the tubular structure being vented, a conducting shield disposed on the outside of the tubular structure, said shield being in electrical contact with the electrode means at one end of the tubular structure and extending toward the other end thereof, and an enclosing insulating member directly engaging said other end of the tubular structure adjacent the end of the shield and extending axially over said shield.

4. A lightning arrester comprising a tubular structure having an internal surface of material capable of evolving gas when exposed to an electric arc, electrode means disposed at opposite ends of said tubular structure, at least one of said electrode means extending into the tubular structure to establish an internal discharge path between the electrodes, and at least one end of the tubular structure being vented, a conducting shield disposed on the outside of the tubular structure, said shield being in electrical contact with the electrode means at one end of the tubular structure and extending toward the other end thereof, said other end of the tubular structure being tapered, and an enclosing insulating member having an internally tapered end portion engaging the tapered end of the tubular structure, said insulating member extending axially over said shield.

5. A lightning arrester comprising a tubular structure having an internal surface of material capable of evolving gas when exposed to an electric arc, electrode means disposed at opposite ends of said tubular structure, at least one of said electrode means extending into the tubular structure to establish an internal discharge path between the electrodes, and at least one end of the tubular structure being vented, a cylindrical conducting shield fitting tightly on the outside of the tubular structure, one end of the tubular structure being tapered, and a cylindrical insulating member having an internally tapered end portion engaging the tapered end of the tubular structure with a tight, sealing engagement, said insulating member extending axially over the shield.

6. A lightning arrester comprising a tubular structure having an internal surface of material capable of evolving gas when exposed to an electric arc, electrode means disposed at opposite ends of said tubular structure, at least one of said electrode means extending into the tubular structure to establish an internal discharge path between the electrodes, and at least one end of the tubular structure being vented, a cylindrical conducting shield fitting tightly on the outside of the tubular structure, one end of the tubular

structure being tapered, and a cylindrical barrier member, said barrier member being made of a plastic insulating material having substantial resilience, the barrier member having an internally tapered end portion engaging the tapered end of the tubular structure with a tight, sealing engagement and extending axially over the shield.

7. A lightning arrester comprising a tubular structure having an internal surface of material capable of evolving gas when exposed to an electric arc, electrode means disposed at opposite ends of said tubular structure, at least one of said electrode means extending into the tubular structure to establish an internal discharge path between the electrodes, and at least one end of the tubular structure being vented, a cylindrical conducting shield fitting tightly on the outside of the tubular structure, said shield being in electrical contact with the electrode means at one end of the tubular structure and extending toward the other end thereof, said other end of the tubular structure being tapered beyond the end of the shield, and a cylindrical insulating member having an internally tapered end portion engaging the tapered end of the tubular structure with a tight, sealing engagement, said insulating member extending axially over the shield.

8. A lightning arrester comprising a tubular structure having an internal surface of material capable of evolving gas when exposed to an electric arc, electrode means disposed at opposite ends of said tubular structure, at least one of said electrode means extending into the tubular structure to establish an internal discharge path between the electrodes, and at least one end of the tubular structure being vented, a cylindrical conducting shield fitting tightly on the outside of the tubular structure, said shield being in electrical contact with the electrode means at one end of the tubular structure and extending toward the other end thereof, said other end of the tubular structure being tapered beyond the end of the shield, and a cylindrical barrier member, said barrier member being made of a plastic insulating material having substantial resilience, the barrier member having an internally tapered end portion engaging the tapered end of the tubular structure with a tight sealing engagement and extending axially over the shield.
